UNITED STATES PATENT OFFICE.

CLARENCE E. SEELEY, OF SPOKANE, WASHINGTON.

GLASS-WASHING APPARATUS.

Application filed October 7, 1919. Serial No. 329,049.

To all whom it may concern:

Be it known that I, CLARENCE E. SEELEY, a citizen of the United States, residing at Spokane, in the county of Spokane, and 5 State of Washington, have invented certain new and useful Improvements in a Glass-Washing Apparatus, of which the following is a specification.

My invention relates to new and useful 10 improvements in glass washing apparatus and more particularly to apparatus of the automatic type.

The primary object of the invention aims 15 to provide a device of the above character comprising means for automatically drawing and ejecting water through perforated arms upon the interior and exterior surfaces of the glass in one operation.

A further object of the invention is to 20 provide a device of the above mentioned character comprising a plurality of perforated arms carrying brushes, means for revolving the arms, a valve arrangement whereby water is forced through the arms 25 and forcibly ejected upon the interior and exterior surfaces of the glass in the one operation, said structure being simple, easy to operate, reliable in such operation, and inexpensive to manufacture.

30 Other objects and advantages of the invention will be apparent during the course of the following description.

In the accompanying drawings forming 35 a part of this specification and in which like numerals are employed to designate like parts throughout the same,

Figure 1, is a vertical sectional view through the axis of the apparatus;

Figure 2, is a detailed sectional view of 40 the connection between the telescoping sections, and

Figure 3, is a top view of the apparatus showing the arrangement of the brushes.

In the drawings, wherein for the purpose 45 of illustration, I have shown a preferred embodiment of my invention, the numeral 5 designates a metallic receptacle of a well known type, containing water or other suitable washing fluid which may be placed 50 upon a stove or gas range in order to heat the same. Positioned centrally within the receptacle is a vertical tubular casing 6 which has its lower end closed by the flap valve 7 which is normally seated upon 55 the annular flange 8 at the lower end of the casing. The casing is supported a

substantial distance above the bottom of the receptacle by the brace strips 9 which are inclined at an angle, having their upper ends attached to the casing by means of rivets 10. The lower ends of the strips are bent at an angle, as at 11, being attached to the bottom by solder or any other suitable means. Telescopically received within the casing 6 is a tube 12 of smaller diameter 65 than the casing and provided with an outwardly extending annular flange 13. A collar 14 is secured within the upper end of the casing 6 by the rivets 10 so that when the tube is in an extended position the annular flange 13 will abut with the collar, thus limiting the upward movement thereof. A helical rib 15 is formed integrally 70 upon the outer surface of the tube being engaged by the helical groove 16 formed in the collar 14 as more clearly shown in Figure 2. Thus it is obvious that when the tube 12 is depressed a rotary movement is imparted thereto due to the movement of the rib 15 in the groove 16. In order that the 75 tube 12 will be normally held in an extended position, a coil spring 17 is mounted within the casing 6, the lower end of which is seated upon the annular collar 8 while the upper end engages the rubber washer 18 which 80 is positioned between the spring and the annular flange 13 to form a water tight connection. Within and adjacent the upper end of the tube 12 a partition 19 is formed having an annular opening 20 therethrough 85 which is normally closed by the flap valve 21 which is pivotally secured to the edge 90 of the opening.

The upper end of the tube 12 is exteriorly 95 screw threaded to detachably receive the hemispherical shaped cap 22. Projecting vertically from the center of the cap 22 is a hollow arm 23 which is provided with perforations 24 throughout its entire length. A tubular brush head 25 is mounted on the 100 arm 23 and is provided with perforations which register with the perforations in the tubular arm. The brush head is held upon the arm by the pin 26, the head of which forms a rest for the glass 27. The upper 105 end of the brush head is tapered, as at 28, so that the bristles 29 which project from the brush head will contact with both the sides and bottom of the glass, thus thoroughly cleansing the same. Extending laterally from opposite sides of the cap 22 are 110 tubular arms 30 which are inclined up-

wardly until they are a substantial distance beyond the sides of the glass when they are bent upwardly at right angles forming arms parallel with the central arm 23. These 5 arms are also provided with tubular brush heads 31 which have bristles 29 extending from the side nearest the glass, so as to form a brushing element for cleaning the exterior surface. These arms may also be provided with perforations in order that the 10 exterior of the glass may be washed as well as the interior.

In operation, the glass 27 is inverted and placed over the central arm 23, being supported upon the head of the pin 26. When 15 in this position the bristles on the central arm will contact with the interior surface of the glass while the bristles on the outer arms will contact with the exterior surface 20 of the glass. While in this position the casing 6 will be filled with water and upon depressing the glass a rotary movement will be imparted to the arms through the engagement of the helical rib 15 with the similar shaped groove 14, thus revolving the 25 brushes about the surface of the glass. In this same operation, a pressure will be created within the casing 6 of sufficient force 30 to close the valve 7 and force the contents within the casing up through the valve 21 and the arms, ejecting the same upon the exterior and interior surfaces of the glass. After the tube 12 has been entirely depressed the coil spring 17 will automatically 35 return it to its normal position, whereupon a suction will be created to the extent that the valve 7 will be lifted from its seat and water drawn from the receptacle 5 into the casing 6 for the 40 next operation of the apparatus. Thus it is obvious that a simple and inexpensive apparatus has been produced which will effectually and thoroughly cleanse glasses or other similar articles through an automatic

operation which accomplishes the result in 45 one movement. Furthermore, it must be noted that the device is of such a structure that it may be easily taken apart in order that the same may be kept in a sanitary 50 condition.

It is to be understood that the form of my invention herewith shown and described, is to be taken as a preferred example of the same, and that certain changes in the shape, size and arrangement of parts may be resorted to without departing from the spirit 55 of the invention or the scope of the subjoined claim.

Having thus fully described my invention, I claim:

In combination with a reservoir, a tubular casing supported centrally thereof, a tube telescoping the casing and having a helical rib formed integral thereon, a collar secured within the top of the casing having 65 a helical groove, said rib cooperating with said groove to impart a rotary movement to the tube when the latter is reciprocated, a semi-spherical cap connected to the upper 70 end of said tube, hollow spray arms radiating from said cap and having their outer extremities bent upwardly at right angles, a central arm extending vertically from said cap, the said arms being of equal length and having a plurality of spaced apertures, tubular brush heads detachably mounted on 75 said arms having openings registering with said apertures, bristles projecting from the central head forming a circular brush, and bristles projecting from the inner side of 80 the outer heads engaging the bristles of the center head.

In testimony whereof, I have affixed my signature in the presence of two witnesses.

CLARENCE E. SEELEY.

Witnesses:

R. S. HAMILTON,
MARTIN KELTY.
